WO 2005051149 6/2005

Primary Examiner — Ricky Pham

(57) **CLAIM**

We claim the ornamental design for a blender, as shown and described.

DESCRIPTION

FIG. 1 is a front perspective view of the blender of the present invention;

FIG. 2 is a rear perspective view of the blender of FIG. 1; FIG. 3 is a front elevation view of the blender of FIG. 1; FIG. 4 is a rear elevation view of the blender of FIG. 1; FIG. 5 is a first-side elevation view of the blender of FIG. 1; FIG. 6 is a second-side elevation view of the blender of FIG. 1;

FIG. 7 is a top plan view of the blender of FIG. 1; and, FIG. 8 is a bottom plan view of the blender of FIG. 1. The broken lines shown in the drawings are for illustrative purposes only and form no part of the claimed design.
